UNITED STATES PATENT OFFICE.

HENRY FORD, OF DEARBORN, MICHIGAN.

METHOD OF MAKING SPARK PLUGS.

Application filed October 5, 1927. Serial No. 224,096.

The object of my invention is to provide a spark plug of simple, durable, and inexpensive construction.

Still a further object of my invention is to provide a spark plug wherein the porcelain may be extruded in the form of a bar from an extruding machine instead of being molded or cast and subsequently ground or machined in order to bring the porcelain to its final shape.

Still a further object of my invention is to provide a spark plug wherein the metal casing or shell thereof may be cast on to the spark plug in permanent molds whereby the said casing may be cast in its final form and nothing need be done after the casting except the thread thereon will have to be trued up and the electrode bent to proper shape.

Still a further object of my invention is to provide a spark plug wherein the metal casing may be cast directly on to the porcelain and the electrode wire may be placed in the mold so that the casing will be cast around this wire thereby providing means for holding the electrode wire into the casing accurately and insuring good electrical contact therewith.

With these and other objects in view my invention consists in the arrangement, construction, and combination of the various parts of my improved spark plug, as described in the specification, claimed in the claims, and illustrated in the accompanying drawings, in which:

Figure 1 shows a side elevation of a spark plug constructed in accordance with my invention.

Figure 2 shows a vertical central sectional view of the spark plug illustrated in Figure 1.

Figure 3 shows a vertical central enlarged sectional view through the porcelain and the casing illustrating the bond between the casing and the porcelain.

Referring to the accompanying drawing I have used the reference number 10 to indicate the porcelain of a spark plug. By referring to Figure 2 it will be noted that this porcelain is of cylindrical shape throughout its length, so that it may be formed by being extruded from an extruding machine in the form of a continuous bar, and then this bar may be cut to form blanks for porcelain.

When these blanks have been so cut, then the recess 11 may be formed in one end thereof

by any suitable means and the electrode wire 12 may be inserted therein. The hole for this electrode wire may be either formed at the time that the bar is extruded from the extruding machine, or it may be drilled subsequently. The electrode wire is preferably fastened into the porcelain by having an enlarged portion or shoulder 13 formed thereon by the upsetting process and then the upper end of the electrode wire is threaded as at 14 so that a nut 15 may be screwed down on the electrode to draw the shoulder 13 up against the bottom of the recess 11 to thereby lock the electrode into the porcelain and form a gas tight joint there-between.

When the porcelain has been so formed, it is then placed in a suitable permanent mold having a recess therein wherein an electrode wire 16 has been inserted in such position that it will be properly placed when the shell 17 has been cast. The shell 17 is then cast by pouring molten metal into the mold to form the casing in the same manner as castings have been made, in the past. The surface of the porcelain which will come into contact with the molten metal, is preferably coated with a material 18 which will serve as a heat insulator, a cushion to protect the porcelain from the molten iron, a gas seal, and a binder to hold the spark plug together. I have found flake graphite very satisfactory for this purpose but do not desire to limit myself thereto.

The porcelain may be glazed at any suitable stage in the manufacture of the plug.

It will be noted that when the casting is made, the molten metal will flow around the end of the electrode 16 which extends into the mold whereby the metal will unite itself with the material of the electrode at least by surface cohesion so that the parts will be permanently united and a high electrical conductivity will be secured.

Among the many advantages resulting from the use of my improved spark plug, it should first be pointed out that the screw machine operations ordinarily necessary in connection with forming the shell are eliminated and the assembly of the spark plug is simplified. The proper positioning of the parts of the plug is also insured. A satisfactory bond between the electrode 16 and the shell is also insured without additional operations. The porcelain for this spark plug may be extruded from an extruding machine instead of being cast and then

ground or machined to shape so that the forming of the porcelain is much cheaper and faster than in connection with other methods of forming porcelains with which I am familiar. The electrode is fastened into the porcelain and a gas tight joint is insured with a minimum of parts and operations.

Some changes may be made in the manufacture of my improved spark plug without departing from the spirit of my invention, and it is my intention to cover by my claims such changes as may be reasonably included within the scope thereof.

I claim as my invention:

1. The method of forming a spark plug consisting of forming the porcelain, coating the porcelain with a material adapted to initially form a heat insulator and cushion to protect the porcelain, from molten iron and to subsequently form a gas seal between the iron and porcelain and then casting an iron shell onto the porcelain.

2. The method of forming a spark plug consisting of forming the porcelain, coating the surface of the porcelain with flake graphite, and then casting an iron shell on the coated porcelain.

HENRY FORD.
